(57) **CLAIM**

The ornamental design for a sports-ball-shaped refrigerator, as shown and described.

DESCRIPTION

FIG. 1 is a front perspective view of the first embodiment of a sports-ball-shaped refrigerator, showing my new design;

FIG. 2 is a front view thereof;

FIG. 3 is a rear view thereof;

FIG. 4 is a right-side view thereof;

FIG. 5 is a left-side view thereof;

FIG. 6 is a top plan view thereof;

FIG. 7 is a bottom plan view thereof;

FIG. 8 is a front perspective view of the second embodiment of a sports-ball-shaped refrigerator, showing my new design;

FIG. 9 is a front view thereof;

FIG. 10 is a rear view thereof;

FIG. 11 is a right-side view thereof;

FIG. 12 is a left-side view thereof;

FIG. 13 is a top plan view thereof;

FIG. 14 is a bottom plan view thereof;

FIG. 15 is a front perspective view of the third embodiment of a sports-ball-shaped refrigerator, showing my new design;

FIG. 16 is a front view thereof;

FIG. 17 is a rear view thereof;

FIG. 18 is a right-side view thereof;

FIG. 19 is a left-side view thereof;

FIG. 20 is a top plan view thereof;

FIG. 21 is a bottom plan view thereof;

FIG. 22 is a front perspective view of the fourth embodiment of a sports-ball-shaped refrigerator, showing my new design;

FIG. 23 is a front view thereof;

FIG. 24 is a rear view thereof;

FIG. 25 is a right-side view thereof;

FIG. 26 is a left-side view thereof;

FIG. 27 is a top plan view thereof; and,

FIG. 28 is a bottom plan view thereof.

The dot-dashed broken lines disclose unclaimed boundaries of the claimed design; the evenly broken lines disclose unclaimed subject matter.

1 Claim, 28 Drawing Sheets
